Attorney, Agent, or Firm—Martha G. Pugh

[57] **CLAIM**

The ornamental design for an adjustable level, substantially as shown and described.

DESCRIPTION

FIG. 1 is a fragmentary perspective view of one end of the adjustable level showing my new design;

FIG. 2 is a rear perspective view of the level indicator slide shown separately for ease of illustration;

FIG. 3 is a top plan view of FIG. 1 on a reduced scale, the opposite end shown broken away to indicate indeterminate length.

The bottom surfaces of all figures are flat, plain, and unornamented.
